UNITED STATES PATENT OFFICE

CLAUDE H. DANIELS, OF NEWTON CENTER, MASSACHUSETTS

DESIGN FOR A SHOE

Application filed February 2, 1933. Serial No. 47,092. Term of patent 14 years.

To all whom it may concern:

Be it known that I, CLAUDE H. DANIELS, a citizen of the United States, and a resident of Newton Center, in the county of Middlesex and State of Massachusetts, have invented a new, original, and ornamental Design for a Shoe, of which the following is a specification, reference being had to the accompanying drawing, forming part thereof.

Referring to the drawing,

The figure is a side perspective view of a shoe showing my new design.

The shading in the drawing is to illustrate contrasting colors.

I claim:

The ornamental design for a shoe, substantially as shown and described.

In witness whereof, I hereunto subscribe my name this 6th day of January, A. D. 1933.

CLAUDE H. DANIELS.
